FIG. 1 is an upper rear perspective view of a urinary flow rate measurement device of my design;

FIG. 2 is an upper front perspective view thereof;

FIG. 3 is a lower rear perspective view thereof;

FIG. 4 is a lower front perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof; and,

FIG. 10 is a bottom view thereof.
